US00D935237S

(12) United States Design Patent (10) Patent No.: US D935,237 S
(45) Date of Patent: * Nov. 9, 2021

(54) CABINET

(71) Applicant: Walker Edison Furniture Company LLC, West Jordan, UT (US)

(72) Inventors: Matthew Davis, Millcreek, UT (US); Brad Bonham, Draper, UT (US); Richard A. Packer, Kaysville, UT (US); Tiffany Duhadway, Salt Lake City, UT (US)

(73) Assignee: Walker Edison Furniture Company LLC, West Jordan, UT (US)

() Term: 15 Years

(21) Appl. No.: 29/756,291

(22) Filed: Oct. 27, 2020

Related U.S. Application Data

(62) Division of application No. 29/698,919, filed on Jul. 22, 2019.

CLAIM

The ornamental design for a cabinet, as shown and described.

DESCRIPTION

FIG. 1 is a front perspective view of a cabinet showing the new design;

FIG. 2 is a front elevation view thereof showing the sliding door slid to the left of the cabinet;

FIG. 3 is another front elevation view thereof showing the sliding door slid to the right of the cabinet;

FIG. 4 is a back elevation view thereof;

FIG. 5 is a top plan view thereof;

FIG. 6 is a bottom plan view thereof;

FIG. 7 is a right elevation view thereof; and,

FIG. 8 is a left elevation view thereof.

The broken lines shown in the Figures illustrate portions of the cabinet that form no part of the claimed design.
